UNITED STATES PATENT OFFICE.

JOHN B. SALTERINI, OF NEW YORK, N. Y.

DESIGN FOR A FLOOR LAMP.

Application filed August 22, 1928. Serial No. 27,922 Term of patent 3½ years.

To all whom it may concern:

Be it known that I, JOHN B. SALTERINI, a citizen of the United States, residing at New York, county of New York, and State of New York, have invented a new, original, and ornamental Design for a Floor Lamp, of which the following is a specification, reference being had to the accompanying drawing, forming part thereof.

The figure is a perspective view of the floor lamp.

I claim:

The ornamental design for a floor lamp, as shown.

JOHN B. SALTERINI.
